UNITED STATES PATENT OFFICE.

FRANK MORGAN, OF MELROSE, MASSACHUSETTS.

STARTING DEVICE FOR INTERNAL-COMBUSTION ENGINES.

1,093,065.

Specification of Letters Patent. Patented Apr. 14, 1914.

Application filed March 29, 1913. Serial No. 757,491.

To all whom it may concern:

Be it known that I, FRANK MORGAN, a subject of the Kingdom of Great Britain, residing at Melrose, in the county of Middlesex and State of Massachusetts, have invented a new and useful Improvement in Starting Devices for Internal-Combustion Engines, of which the following is a specification, reference being had therein to the accompanying drawings.

This invention relates to starting devices for internal combustion engines in which a compressed fluid is utilized as the operating medium.

15 The principal object of the invention is to provide a starting apparatus efficient and simple in construction and operation and of low cost as to both initial and operating expense.

20 Another object of the invention is to provide a starting device of the foregoing character which is entirely self contained and which requires no extraneous supply of motive power.

25 Other objects of the invention will be more specifically pointed out and described hereinafter.

In the accompanying drawings illustrating the preferred form of my invention, Figure 1 is a side elevation of a starting device constructed and operated in accordance with my invention as applied to a four cylinder engine; Fig. 2 is a vertical central sectional view of a pump provided for compressing the actuating fluid and a valve mechanism for controlling the flow of the compressed fluid to the various cylinders of the engine and Fig. 3 is a cross sectional view of the said valve on line 3-3 in Fig. 2 looking from right to left.

Briefly, the illustrated embodiment of the invention comprises a reservoir containing a supply of fluid under compression, means controlling the flow of fluid from the reservoir to the cylinders of the engine and means operated by the engine for maintaining the pressure in the reservoir.

Referring to Fig. 1 of the drawings, 4, 5, 6 and 7 designate the cylinders of a four cylinder internal combustion engine, 8 a main shaft, 9 a crank case, and 10 a fly wheel mounted on the main shaft, all of which parts are of old and well known construction. The position of the pistons in the various cylinders is indicated by dotted lines.

A reservoir 12 of suitable form and construction is provided for holding a supply of compressed liquid, preferably air, which reservoir is connected to a pump 14 by a pipe 15 and to the cylinders of the engine by a pipe 16 leading to a rotary valve 17 and thence by pipes 18, 19, 20 and 21 to cylinders 4, 5, 6 and 7 respectively. The pump provides and maintains the pressure in the reservoir which flows into the latter from the former through the pipe 15 and the compressed fluid in the reservoir flows outwardly through the pipe 16 to the valve 17 whence it is directed to the cylinders in proper sequence.

The pump and valve are operated by the engine and to secure this result I preferably employ the construction shown on an enlarged scale in Fig. 2 especially. The pump 75 comprises a casing 23 having an integral cylinder 24 within which is a piston 25 connected by a piston-rod 26 to a crank shaft 27 mounted in journal bearings 28 and 29 which are part of the casing. Upon the 80 outer end of the shaft 27 is secured a gear wheel 30 which meshes with a gear wheel 31 mounted on the main shaft 8 of the engine. The compression end of the pump cylinder may be provided with suitable 85 valves 33 and 34, the former being an inlet valve to admit air to the cylinder when the pump piston is on its suction stroke and the latter being an outlet valve to permit the air under compression to flow from the 90 cylinder to the reservoir when the pressure in the cylinder exceeds that in the reservoir. Any suitable form of valve may be employed in this connection, that shown comprising a ball 35, held in a seated position 95 to close the valve by a spring 36. The cylinder of the pump may be provided with suitable cooling fins 37.

The valve 17 is preferably constructed as follows: At the end of the crank shaft 27 opposite the gear wheel the end is extended and hollowed out to form a chamber 38 which is provided with a port 39. The bearing 29, which constitutes the valve casing, is provided with lateral extensions 40, screw 100 threaded to receive the ends of the pipes 18, 19, 20 and 21 leading to the various cylinders of the engine and each extension 40 is provided with a passage 41 so that when the crank shaft 27 rotates the port 39 registers with the passages 41 in sequence. The end of the bearing 29 is provided with a

passage 42 and screw threaded to receive the pipe 16 into the chamber 38 and thence into the pipes leading to the cylinder through the port 34.

5 To control the flow of the compressed fluid from the reservoir 12 a valve 43 of suitable construction is arranged in the pipe 16, said valve being controlled by a rod 44 or other means, to permit the valve to be 10 opened and closed from a distance.

The operation of my device is as follows: The dotted outlines in Fig. 1 show the normal position of the pistons when the engine is at rest with the valve 43 closed. To 15 start the engine the valve 43 is opened which permits the compressed fluid to flow from the reservoir through the pipe 16 into the valve 17 through the port 39 and into one of the pipes to the proper cylinder. In order 20 that the compressed fluid may at all times be introduced through the valve 17 into the proper cylinder, the gear wheels 30 and 31 are made of such size that the wheel 30 makes one revolution while the main shaft 25 makes two, thereby permitting the air to be introduced at the proper time in the operation of a four cycle engine. This result is secured by proper adjustments which may be made by any one skilled in the art. 30 When the compressed fluid is introduced into the proper cylinder it causes the piston to be moved downwardly and the engine to be started thereby revolving the main shaft. As this shaft revolves it turns the crank 35 shaft 27 and when the latter has been turned a quarter revolution the port 39 then registers with another pipe leading to another cylinder and the compressed fluid is allowed to flow into the next cylinder. This operation 40 is continued and the compressed fluid is introduced into one cylinder after the other until the engine has been fully started, when the valve 43 may be closed and the engine then operated in the usual manner 45 by ignition means.

Preferably the pump is operated only when the pressure in the tank falls below a certain minimum and to accomplish this result the gear wheel 30 is loosely mounted 50 on the crank-shaft 27 and is provided with any suitable form of clutch so that it may be thrown into engagement with a collar 46 secured on the crank-shaft 27 and thereby rotate the same. The form of clutch shown 55 in the drawings consists of a pin 47 fixed on the hub of the gear wheel 30 which is adapted to engage a corresponding recess 48 on the collar 46. The opposite side of the hub of the gear wheel 30 is provided with 60 an extension 49 having a circumferential groove 50 and this groove may be engaged

by a lever, not shown, which may be operated from a distance in the well known manner used in operating clutches. The gear 65 31 is of such thickness that the gear wheel 30 meshes with it whether it is running wild or not. Whenever the pressure in the reservoir falls below the minimum, the clutch may be operated whereby the gear wheel 30 will turn the crank-shaft 27 and 70 operate the pump, thereby increasing the pressure in the reservoir. This arrangement saves wear on the pump and the valve. To prevent unusual pressure being generated therein, a safety valve 45 may be arranged on the reservoir to permit the excess 75 pressure to blow off.

It will be noticed that my device is of extreme simplicity and that it is entirely 80 self contained; that it requires no electrical or other extraneous power to operate it and that it is so constructed that it cannot get out of order or become inoperative.

My invention may be applied to internal combustion engines having a greater or a 85 less number of cylinders than four by making slight constructional changes, which will be apparent to any one skilled in the art, from the foregoing description.

Although I have shown and described 90 herein the preferred embodiment of my invention, various changes may be made in the construction and arrangement of the same without departing from my invention and I desire to claim the same broadly except 95 where specifically limited in the following claim.

What I claim is:—

A starting device for internal combustion engines having, in combination, a multiple cylinder internal combustion engine, a reservoir for compressed fluid, a pump for compressing the fluid and having journal bearings, ports in one of said bearings, pipes connecting the ports and the cylinders of 105 the engine respectively, a chamber hollowed into one end of the crank-shaft of said pump, a port in the crank-shaft leading into the chamber and adapted to register successively with the ports in the pump-bearing so as thereby to supply the compressed fluid to the cylinders of the engine 110 respectively.

In testimony whereof, I hereunto set my hand in the presence of two subscribing 115 witnesses, this the twenty fifth day of March, 1913.

FRANK MORGAN.
